INVENTOR:
Dudley Farrand,
BY
Fraentzel and Richards,
ATTORNEYS

UNITED STATES PATENT OFFICE.

DUDLEY FARRAND, OF NEWARK, NEW JERSEY.

EXHAUST SILENCER.

Application filed May 12, 1920, Serial No. 380,732. Renewed September 14, 1923.

To all whom it may concern:

Be it known that I, DUDLEY FARRAND, a citizen of the United States, residing at Newark, in the county of Essex and State of New Jersey, have invented certain new and useful Improvements in Exhaust Silencers; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in centrifugal machines or apparatus; and, the present invention has reference, more particularly, to a novel centrifugal exhauster which is especially adapted for application to the exhaust-pipe of a steam-engine, or the like, and is adapted to be driven from the exhausting medium, the device thereby acting as an exhaust-silencer.

The present invention, therefore, has for its principal object to provide a novel and simply constructed apparatus of the general character hereinafter more fully set forth, which is readily adapted for attachment to the exhaust pipe of a steam engine, or the like, the apparatus being provided with an impeller which is driven from the escaping exhaust, and by its action causes such exhausting medium to perform a certain amount of work, whereby its force is expended and the usual noise of the escaping medium is silenced.

With the various objects of the present invention in view, the said invention consists, primarily, in the novel exhaust silencer hereinafter more fully set forth; and, the said invention consists, furthermore, in the novel arrangements and combinations of the several parts of the device, all of which will be more fully described in the following specification, and then finally embodied in the clauses of the claims which are appended to and which form an essential part of the said specification.

The invention is illustrated in the accompanying drawings, in which:

Figure 1 is a side elevation of the exhaust silencer, showing one embodiment of the principles of the present invention; Figure 2 is an end view of the same, looking in the direction of the arrow X in said Figure 1;

and Figure 3 is a top or plan view of the exhaust silencer.

Figure 4 is a side view of an impeller used with the device or apparatus; and Figure 5 is a transverse vertical sectional representation of the same.

Similar characters of reference are employed in said above described views, to indicate corresponding parts.

Referring now to the several figures of the drawings, the reference-character 1 indicates one form of exhaust silencer, made according to and embodying the principles of the present invention, the same comprising a pair of chambered half-sections or casing-members, as 2 and 3, formed with semi-tubular outlet-portions, as 4 and 5. As shown, the respective half-sections or casing-members 2 and 3, and the respective outlet-portions 4 and 5, are respectively flanged, as at 6 and 7, said flanges being placed opposite each other, as represented in Figures 2 and 3 of the drawings, and being provided with

registering holes for the reception of bolts 8 and nuts 9 on said bolts, whereby the said members are secured in an assembled relation, and whereby a main impeller-shell or casing of the general configuration shown in the drawings is provided. As illustrated, the exhaust or discharge end provided by the assembled outlet-portions 4 and 5, may also be provided with laterally extending flanges 10 and 11, respectively, provided with bolt-receiving holes 12, for the attachment to the annular flange thus provided of a conveyor pipe or tube, as will be evident.

As indicated in dotted outline in said Figure 1 of the drawings, the half-sections or casing-members 2 and 3 are, respectively, formed in their sides with oppositely placed inlet-ports 13, which are preferably of an elliptical or elongated shape, but which may be of any other conformation, suitable for the purposes of the present invention. The said inlet-ports, as represented, are located opposite each other, at points above a plane passed horizontally through the centers of the said half-sections or casing-members 2 and 3, and connected with said half-sections

or casing-members 2 and 3, and enclosing the respective inlet-ports 13, are a pair of rearwardly extending and tubular conveyor-ducts or elements, as 14 and 15, which are preferably annularly flanged, as at 16 and 17, for the attachment thereto of the flanged members 19 and 20 of a Y-shaped or other

100

115

suitably shaped pipe-fitting or element 21, the inlet-portion of which may also be flanged, as at 22, for attachment of said fitting in a suitable manner to the exhaust-pipe of a steam-engine, or any other noise-producing source of exhausting medium.

The two half-sections or casing-members 2 and 3 are provided at their centers with oppositely placed bearings 23 and 24, in 10 which are rotatably disposed the journal-ends 26 and 27 of an impeller shaft 28.

The impeller, as will be seen from an inspection of Figures 4 and 5 of the drawings, consists, essentially, of a hub-portion 29, 15 suitably mounted upon the impeller-shaft, which is preferably suitably curved, as at 30, see Figure 5, and terminates in a centrally disposed annular dividing wall-member, as 31. Extending laterally on opposite sides of said wall-member, and connected with the said hub-portion 29, are a number of radially disposed impeller-blades 32, all arranged so as to provide a number of medium-receiving and carrying pockets, 25 in which the exhaust-medium finally exerts its power, and is expelled into the expanding outlet-duct, from which it is carried and forced into the discharging or exhausting outlet of the complete exhaust-silencer, as 30 will be clearly understood. The impeller, as will be seen from an inspection of said Figure 4, may also be provided with an arrangement of short blades, as 33, which extend on opposite sides of the wall-member 31, from the peripheral edge of said wall-member into the respective pockets formed by the said wall-member 31 and the respective impeller-blades 32.

Having in the foregoing, described one 40 general construction of exhaust-silencer, and the general arrangements and combinations of the various parts thereof, all made according to and embodying the principles of the present invention, it will be clearly evident 45 from an inspection of the several figures of the drawings, just in what manner the apparatus or device operates, when an exhausted medium, such as exhaust steam, is admitted through the inlet-ports, on opposite 50 sides into the interior of the apparatus and against the impeller rotatably mounted therin.

When this action takes place the exhausting medium performs its final work against 55 the vanes or blades of the impeller, thus rotating the same, and at the same time breaking up the exhausted medium in such a manner that the noise usually accompanying the same is silenced and the medium is finally 60 discharged at the discharge-end of the apparatus, either into the air or into a pipe or other conveyor, without noise.

Of course I am aware that some changes 65 may be made in the general arrangements and combinations of the several parts of the

apparatus without departing from the scope of the present invention, as defined in the claims which are appended to the foregoing specification. Hence, I do not limit my present invention to the exact arrangements and 70 combinations of the several devices and parts as described in the said specification, nor do I limit myself to the exact details of the construction of the said parts, as illustrated in the accompanying drawings. 75

I claim:—

1. An exhaust silencer comprising a chambered-casing having a discharge-opening, an impeller rotatably mounted in said casing, inlet-ports on opposite sides of said casing, conveyor-ducts connected with said casing, each conveyor-duct being in communication with an inlet-port, and means connected with the inlet-openings of said conveyor-ducts for admission of an exhausted medium 80 into said conveyor-ducts for actuating said impeller.

2. An exhaust silencer comprising a chambered casing having a discharge-opening, an impeller rotatably mounted in said casing, inlet-ports on opposite sides of said casing, conveyor-ducts connected with said casing, each conveyor-duct being in communication with an inlet-port, and means connected with the inlet-openings of said conveyor-ducts for admission of an exhausted medium into said conveyor-ducts for actuating said impeller, said impeller comprising a hub-portion mounted upon the impeller-shaft, a centrally disposed annular wall-member extending vertically from said hub-portion, and impeller vanes extending laterally from said wall-member.

3. An exhaust silencer comprising a chambered-casing having a discharge-opening, an impeller rotatably mounted in said casing, inlet-ports on opposite sides of said casing, conveyor-ducts connected with said casing, each conveyor-duct being in communication with an inlet-port, and a Y-shaped tubular 105 inlet fixture connected with the inlet-openings of said conveyor-ducts for admission of an exhausted medium into said conveyor-ducts for actuating said impeller.

4. An exhaust silencer comprising a chambered-casing having a discharge-opening, an impeller rotatably mounted in said casing, inlet-ports on opposite sides of said casing, conveyor-ducts connected with said casing, each conveyor-duct being in communication 110 with an inlet-port and a Y-shaped tubular inlet fixture connected with the inlet-openings of said conveyor-ducts for admission of an exhausted medium into said conveyor-ducts for actuating said impeller, said impeller comprising a hub-portion mounted upon the impeller-shaft, a centrally disposed annular wall-member extending vertically from said hub-portion, and impeller vanes extending laterally from said wall-member. 115

5. The herein-described exhaust silencer comprising an impeller-casing consisting of a pair of chambered half-sections and correspondingly shaped semi-tubular outlet-portions, means for securing said half-sections and outlet-portions together to provide said impeller-casing, each half-section being provided with a bearing-portion and an inlet-port, a conveyor-duct connected with each 10 half-section, each conveyor-duct being in communication with an inlet-port, an impeller-shaft rotatably mounted in said bearing-ports, an impeller mounted upon said shaft, and means connected with the inlet- 15 openings of said conveyor-ducts for admission of an exhaust medium into said conveyor-ducts for actuating said impeller. 16
6. The herein-described exhaust silencer comprising an impeller-casing consisting of 20 a pair of chambered half-sections and correspondingly shaped semi-tubular outlet-portions, means for securing said half-sections and outlet-portions together to provide said impeller-casing, each half-section being 25 provided with a bearing-portion and an inlet-port, a conveyor-duct connected with each half-section, each conveyor-duct being in communication with an inlet-port, an impeller-shaft rotatably mounted in said bearing-ports, an impeller mounted upon said shaft, and means connected with the inlet- 30 openings of said conveyor-ducts for admission of an exhaust medium into said conveyor-ducts for actuating said impeller, said impeller, comprising a hub-portion mounted upon the impeller-shaft, a centrally disposed annular wall-member extending vertically from said hub-portion, and impeller vanes extending laterally from said wall-member. 35
7. The herein-described exhaust silencer comprising an impeller-casing consisting of a pair of chambered half-sections and correspondingly shaped semi-tubular outlet-portions, means for securing said half-sections 40 and outlet-portions together to provide said impeller-casing, each half-section being provided with a bearing-portion and an inlet-port, a conveyor-duct connected with each half-section, each conveyor-duct being in 45 communication with an inlet-port, an impeller-shaft rotatably mounted in said bearing-ports, an impeller mounted upon said shaft, and a Y-shaped tubular inlet fixture connected with the inlet-openings of 50 said conveyor-ducts for admission of an exhaust medium into said conveyor ducts for actuating said impeller. 55
8. The herein-described exhaust silencer comprising an impeller-casing consisting of 60 a pair of chambered half-sections and correspondingly shaped semi-tubular outlet-portions, means for securing said half-sections and outlet-portions together to provide said impeller-casing, each half-section being pro- 65 vided with a bearing-portion and an inlet- port, a conveyor-duct connected with each half-section, each conveyor-duct being in communication with an inlet-port, an impeller-shaft rotatably mounted in said bearing-ports, an impeller mounted upon said 70 shaft, and a Y-shaped tubular inlet fixture connected with the inlet-openings of said conveyor-ducts for admission of an exhaust medium into said conveyor ducts for actuating said impeller, said impeller comprising a hub-portion mounted upon the impeller-shaft, a centrally disposed annular wall-member extending vertically from said hub-portion, and impeller vanes extending laterally from said wall-member. 75
9. An exhaust silencer comprising a chambered impeller casing having oppositely directed inlet openings, and a discharge opening, an impeller rotatably mounted in said casing, and means connected with the inlet 80 openings of said casing for conveying an exhaust medium into said casing for actuating said impeller, said impeller comprising a hub-portion mounted upon the impeller-shaft, a centrally disposed annular wall-member extending vertically from said hub-portion. 85
10. An exhaust silencer comprising a chambered impeller casing having oppositely directed inlet openings, and a discharge 90 opening, an impeller rotatably mounted in said casing, a means connected with the inlet openings of said casing for conveying an exhaust medium into said casing for actuating said impeller, said impeller comprising a hub-portion mounted upon the impeller-shaft, a centrally disposed annular wall-member extending vertically from said hub-portion, and impeller vanes extending 95 laterally from said wall-member. 100
11. An exhaust silencer comprising a chambered casing having a discharge opening, an impeller rotatably mounted in said casing, said casing being provided with an elongated inlet-port, a tubular conveyor-duct connected with said casing and in communication with said inlet-port, and means connected with the inlet opening of said conveyor-duct for admission of an exhaust medium into said conveyor-duct for actuating said impeller, said impeller comprising a hub-portion mounted upon the impeller-shaft, a centrally disposed annular wall-member extending vertically from said hub-portion, and impeller vanes extending 110 laterally from said wall-member. 115
- In testimony that I claim the invention set forth above I have hereunto set my hand this 6th day of May, 1920.
